UNITED STATES PATENT OFFICE.

HARRY JONES, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

SEGMENTAL BRAKE-SHOE.

1,129,986.

Specification of Letters Patent. Patented Mar. 2, 1915.

Application filed October 28, 1914. Serial No. 668,941.

To all whom it may concern:

Be it known that I, HARRY JONES, a citizen of the United States, and a resident of Suffern, in the county of Rockland and State of New York, have made and invented certain new and useful Improvements in Segmental Brake-Shoes, of which the following is a specification.

My invention relates to an improvement in brake shoes, and more particularly to such as have been termed "segmental" shoes, that is, a shoe wherein the cast metal body or wearing portion is provided with a plurality of grooves extending from the wearing face substantially to the back of the shoe, in order to avoid the distortion of the shoe when heated by frictional contact with the tread of a wheel. Shoes made in this way are liable to be cracked or broken during handling and transportation by reason of the fact that the slotted body is apt to be distorted or straightened out, the slots or grooves permitting the undue separation of the segments and thereby causing the metal at the back of the shoe to crack or break and possibly become detached from the reinforcing back usually employed in connection with this type of shoe.

The object of my invention is to overcome this danger and to so form the slots, grooves or recesses in the body that but a slight separation of the adjacent segments is permitted, the slots being of such formation that the adjacent segments are interlocked, and prevented from separating to that extent as will permit or allow the shoe to be so straightened out or distorted to an extent likely to permanently injure or destroy the shoe.

With this and other ends in view, my invention consists in certain novel features of construction and combinations of parts as will be hereinafter fully described and pointed out in the claims.

In the accompanying drawings, Figure 1 is a view of a segmental brake shoe constructed in accordance with my invention. Fig. 2 is a longitudinal sectional view taken on the line 2-2 of Fig. 1. Fig. 3 is a sectional view taken on the line 3-3 of Fig. 2, looking in the direction as indicated by the arrow.

Referring to the drawings, 5 represents the body of the shoe made of cast iron, the rear side being provided with the attaching

or key lug 6, and with end stops 7. In the shoe is also embedded, at or adjacent to the back thereof, a reinforcing plate or member 8.

The cast metal body of the shoe is provided with a plurality of slots 9, extending from the wearing face of the shoe to, or substantially to, the reinforcing plate 8, these slots being of the peculiar formation as illustrated in Fig. 1 of the drawings; that is, instead of the slots extending directly across the body of the shoe, they are such as to form a lock or key 10, the vertical walls or sides of the lock being dove-tailed or undercut, forming shoulders 11 on one segment, and corresponding shoulders 12 on the other segment of the shoe, the walls or sides of these recesses or grooves being substantially parallel throughout. The result of this formation is that any tendency to straighten the shoe out will bring the shoulders 11 of one section or segment against the shoulders 12 of the adjacent section and preventing anything more than a slight straightening of the shoe, not sufficient, however, to permit of the cracking or breaking of the body beyond the end of the slots or grooves 9. In other words, the segments or sections are interlocked, and remain so, the normal position of the segments permitting them a slight separation while any force or pressure tending to straighten the shoe will bring the locking members into contact.

While I have shown the grooves or recesses of a certain formation or shape, yet it should be understood that such is for illustrative purposes only, and not that these grooves or recesses may not be formed in other ways or of other shapes. In fact, these grooves may take a variety of shapes without departing from the effectiveness of the device, it being necessary only that they be of such shape as to form in effect a key on one segment fitting in a corresponding recess in the wall of the adjacent segment, so that the two segments will interlock when slightly separated.

In the molding of shoes constructed like the foregoing, I prefer to use cores in the mold for the formation of the slots 9, these cores to be made of vitrified clay, or burned fire clay, and permitted to remain in the slots until the shoe goes into service. The slot 9 in the shoe, at the extreme left of Figs. 1 and 2, I have illustrated as being filled

with a core 13, it being understood, however, that the core may be removed upon the completion of the castings. By permitting it to remain, however, until the shoe goes 5 into service, it will assist in preventing any tendency of the shoe to be straightened out while in the tumbling barrel, or while being loaded or unloaded during transportation, the core of course readily disintegrating and falling out of the slot after the shoe 10 has been put into service, and thus giving to the shoe the desired flexibility.

What I claim is:—

1. A brake shoe comprising a body having a groove extending from the wearing face to substantially the back of said shoe, said groove being of such a shape as to form 15 interlocking segments.
2. A brake shoe comprising a body formed with a plurality of transverse grooves separating the same into a plurality of segments, said grooves forming locking members in the adjacent sections to prevent the latter from being separated.
3. A brake shoe comprising a body formed with a plurality of grooves extending from the wearing face to substantially the back of 20

the shoe, and forming a plurality of segments, said grooves being of such shape as to form a key on one segment fitting into a 30 corresponding recess formed in the adjacent section whereby to prevent the separation of said segments.

4. A brake shoe comprising a body having a groove extending from the wearing face to 35 substantially the back of said shoe, said groove being of such shape as to form, when devoid of a core, interlocking segments and containing a core capable of disintegration while the shoe is in service.

40
5. A brake shoe comprising a body formed with a plurality of grooves extending from the wearing face into the body of said shoe, said grooves being of such shape as to form, when devoid of a core, locking members in 45 the adjacent sections, and containing a clay core.

Signed at Suffern, in the county of Rockland and State of New York, this 21 day of October, A. D. 1914.

HARRY JONES.
